UNITED STATES PATENT OFFICE.

CHARLES H. REID, OF DANBURY, CONNECTICUT.

HAT-POUNCING MACHINE.

SPECIFICATION forming part of Letters Patent No. 625,699, dated May 23, 1899.

Application filed March 15, 1897. Serial No. 627,679. (No model.)

To all whom it may concern:

Be it known that I, CHARLES H. REID, a citizen of the United States, residing at Danbury, in the county of Fairfield and State of Connecticut, have invented certain new and useful Improvements in Hat-Pouncing Machines, of which the following is a specification.

My invention relates to hat pouncing or sandpapering, and more particularly to machines which perform the operation of pouncing or sandpapering hats or fabrics formed of felt automatically, and has for one of its objects the production of an automatic machine or device which will operate on every portion of the surface of the fabric alike by or through positive continuous movement of an endless belt upon which is placed or to which is secured the pounce, powder, sand, or other material used in such operation, the speed of the belt and the movement of the hat or fabric in a direction the reverse of the belt each being varied so that no part of the surface of the material operated upon will be cut or worn away to a greater depth or degree than any other part of its surface operated upon.

Heretofore in hat-pouncing machines provided with a hat-pouncing belt the spindle that carries the hat and the pouncing-belt have each been constructed to run at a uniform rate of speed. In this construction the tip of the hat-crown is subjected to a deeper cutting or pouncing than the body of the crown. When the rotation of the spindle is uniform, the surface of the hat in the area of the tip will be presented to the action of the pouncing-belt to an extent exceeding its action on the surface of the body of the crown in the proportion that the circumference of the crown exceeds the circumference of the area of the tip at the point where the pouncing-belt is in contact therewith, if the speed of the belt is uniform. An endless belt forty-four inches in circumference moving at the same rate of speed as a hat-crown twenty-two inches in circumference rotated in a direction opposite the direction of the belt would pass twice over the surface when the two made one complete rotation. If the belt was moving in contact with the surface of the tip at a point where its circumference was eleven

inches, it would pass four times over the surface while making one complete rotation.

One of the objects of my invention is to provide a hat-pouncing machine having means for decreasing the speed of the pouncing-belt while it operates on the tip and means for increasing the speed of the spindle and the movement of the pouncing-belt supporting and swinging mechanism operated therewith, whereby the pouncing-belt is rapidly moved away from the surface of the tip of the crown toward its body or base, thereby preventing the tip from being cut too great a depth. I accomplish the same object when the pouncing-belt is carried in contact with the hat from the base of the crown to the tip by increasing the speed of the spindle and decreasing the speed of the pouncing-belt when the latter reaches the area of the tip. By thus providing for a diversity of motion for the spindle and for the pouncing-belt I am able to pounce the crown of the hat with great nicety, uniformity, and rapidity.

Another object of my invention is to provide an automatic hat-pouncing or sandpapering machine that a workman of ordinary skill and intelligence may operate readily and which will do its work with rapidity and economy.

I accomplish the objects of my invention in the manner and by the means hereinafter described in detail, pointed out, and claimed, reference being made to the drawings accompanying this specification, in which the same characters refer to like parts in all the figures of the drawings.

Figure 1 is a side elevation showing the pouncing-belt in contact with the tip of a hat-crown supported on a block. Fig. 2 is a transverse section on line $x-x$ of Fig. 1, showing the dog pivoted in the arm of the lever that holds the worm-wheel in engagement with the worm of the spindle. Fig. 3 is plan view of my hat-pouncing machine on an enlarged scale. Fig. 4 is a section of the frictional gear-wheel 44, showing details. Fig. 5 shows details of construction of the presser-foot, its supporting arm, and collar. Fig. 6 is a front elevation of the pouncing-belt, its supporting mechanism, and a part of its operating mechanism. Fig. 7 is a cross-section on line $y-y$, Fig. 6,

showing block supporting the belt-pulley that drives the pouncing-belt. Fig. 8 is a cross-section of the pulley that carries one end of the pouncing-belt and also the belt-pulley that drives it. Fig. 9 is a cross-section of the pulley carrying the end of the pouncing-belt opposite the pulley that drives it. Fig. 10 is a cross-section on line $z z$, Fig. 6, showing the shoulder on the end of the sleeve that supports the weighted arm and the nose on the sleeve of the long arm of the angular lever which rocks or swings the pouncing-belt frame when the nose and shoulder interlock.

In carrying out my invention I provide a vertical standard A, having a flared circular base a to form a stable support, the upper end of the standard being provided with a horizontal platform or table B, formed integral therewith or rigidly secured thereon. Two curved standards C C', having their lower ends flared outwardly at right angles to form supports and receive means for attaching them to the table or platform B, rise vertically from the middle of the platform and are provided at the upper ends with collars or sleeves D D', which form bearings for a horizontal spindle E journaled therein. The outer end of the spindle E is provided with a vertical frictional disk F, having a collar f formed concentrically therewith and extending from the outer face of the disk and closely fitting the spindle and being rigidly secured thereon by set-screws passing through threaded apertures in the collar and their ends resting in contact with the surface of the spindle. The opposite or inner end of the spindle E has a block G, removably secured thereto by a chuck H, the jaws $h h$ being opened and closed by the movement of a collar I, which surrounds the spindle near its inner end. This collar is moved back and forth on the spindle E and in and out of contact with the jaws $h h$ of the chuck by a lever K, provided with a handle k and pivotally connected to the collar at its lower end. The lever K is fulcrumed near its lower end between the arms $l l$ of a bracket L by means of a pin l' passing through an aperture in the arms and in the lever, the shank or stem of the bracket L being secured by any suitable means to the top of the journal bearing or collar D'.

The circumference of the spindle E between its journal-bearings D D' is provided with a worm e , which meshes or interlocks with the teeth or spurs m , formed on the circumference of a worm-wheel M, vertically mounted within the curved standards C C' on a short shaft N, rigidly secured in an aperture in the wheel and projecting forward from the face thereof and journaled in a bearing n , formed integral with the arm O of an L or bent lever O o, fulcrumed at its heel to the standard C by a bolt o' , provided with a head and fitted in a threaded aperture in the standard C. The arm O extends across the face of the worm-wheel M and terminates beyond the standard C'. The short arm o of the bent

lever rises vertically from the heel, where fulcrumed, to the height of the upper circumference of the spindle and has pivotally secured to its upper end one end of a connecting-rod or draw-bar P, pivotally attached at its other end to a lever Q, near the lower end thereof, the lower end of the lever being pivotally attached to the arms of the bracket L and its upper end having a handle q for operating it. The face of the standard C' is provided with a projecting pin q' , that supports the outer end of the arm O when the lever is dropped.

The free end of the horizontal arm O of the lever has a lengthwise slot R through the side thereof and has pivoted therein a spring-pressed dog or pawl R', provided with a tail r , which projects parallel with and toward the inner end of the lever. A spiral spring S is secured between the tail r and the lever O. A pintle s passes through apertures in the lever above and below the slot and through the dog or pawl and holds the dog or pawl pivotally therein. The inner edge of the dog is provided with a nose T, which is thrown by the action of the spiral spring S into a recess t , formed in the face of the standard C' at a point opposite the center of the worm-wheel when the latter is lifted by the lever into contact with the worm on the spindle. The face of the worm-wheel has attached thereon a beveled trip or wiper U, which engages with the dog R' when the wheel rotates and throws the nose of the dog out of the recess t and permits the lever-arm O to drop against the pin q' , the rotation of the wheel ceasing the instant the lever draws it out of engagement with the wormed spindle.

A crank V, provided with a weight or counterbalance v at one of its ends, is rigidly secured midway of its ends to the outer end of the shaft N and has pivotally connected with its light end W the end of a link w, the other end of which is pivotally attached to the short arm of a bell-crank or angular lever $x y$, pivotally secured at its elbow to the end of a shaft Z, journaled in a sleeve-bearing z , formed on the end of the arm of a horizontal bracket Z', secured to and supported at the side of the journal-bearing D' on the upper end of the standard C'. The bracket Z' projects outward from its point of attachment for a distance and then extends parallel with the spindle E and terminates beyond the inner end of the block secured thereto and supports the mechanism operating the pouncing or sanding belt.

Two loose grooved pulleys 1 2 are journaled on a short shaft passing through the side of the arm of the horizontal bracket Z' at a point thereon opposite the chuck H on the spindle E. These pulleys 1 2 receive a belt 3 4, which passes around pulley 3', rigidly secured to a frictional disk Z², normally in frictional contact with the face of a disk Z³, mounted on a shaft journaled at each of its ends in a supporting-frame Z⁴, which frame may be se-

cured at any suitable or convenient point above the hat-pouncing machine or adjacent thereto. Secured to the side of the disk Z^3 , concentric therewith, is a pulley $4'$, which may receive a belt from a line-shaft or counter-shaft for imparting motion thereto. The disk Z^2 is mounted on a shaft journaled at each of its ends in a supporting-frame pivotally attached to the frame supporting the disk Z^3 .
 10 The face of each of these disks opposite the pulley therewith is slightly rounded, and these rounded faces are held in contact with each other by a spring which presses the frame of the adjustable or movable disk Z^2 toward the fixed disk Z^3 , the outer circumference of the face of disk Z^2 resting normally in contact with the face of disk Z^3 at a point near the shaft on which it is mounted. When the disks are in their normal position and
 15 disk Z^3 is rotated, disk Z^2 moves at a lower rate of speed than disk Z^3 ; but when the frame carrying disk Z^2 is swung so as to change the position of the faces and bring the outer circumference of the face of disk Z^3 in contact with the face of disk Z^2 near its shaft, disk Z^2 is rotated at its highest speed. When the faces of the disks are in contact near their outer circumferences, their speed
 20 is equal. If the circumference of disk Z^3 where it contacts with Z^2 is twice the circumference of the face of the latter disk where it contacts, then one complete rotation of disk Z^3 will cause two complete rotations of disk Z^2 . Any suitable means may be used for
 25 swinging the pivotally-supported frame, such as a strap or cord attached thereto and within reach of the operator to vary the speed of the disk Z^2 . A full description of this speed-varying device is disclosed in Letters Patent
 30 of the United States No. 128,773, issued July 9, 1872. I do not, however, limit myself to the device here named for varying the speed of the pouncing-belt. I may use any suitable speed-varying device for that purpose in
 35 accomplishing the objects of my invention. The belt is received by the pulley 1, runs thence to and around a grooved pulley 5, supported by the shaft Z, journaled in the sleeve-bearing z, and returns under and around the
 40 pulley 2, axled with pulley 1, or vice versa, it making no difference which of the two pulleys first receives the belt 3 4. A grooved pulley 6 is formed in the face of the wheel that receives the power from the belt 3 4.
 45 The downwardly-projecting arm of the bell-crank lever x y is provided with a sleeve 7, formed integral with its lower end and projecting inwardly. This sleeve 7 receives a shaft 8 therein on which are journaled two
 50 connected loose pulleys 9 10, rigidly formed on each end of a collar 11, the pulley 9 being of less diameter than 10. Pivotally secured at its lower end, on the outer end of the shaft 8, is an arm or standard 12, the upper
 55 end of which is provided with a collar 13, through which passes and to which is rigidly secured by a set-screw the longitudinal arm

or shaft 14 of the frame, in which the pulleys are journaled that carry the pouncing or sandpaper belt 15. The arm 12 is held in a movable upright position by a depending weighted arm 16, that is attached by its upper end to a sleeve 17, secured on the inner end of the shaft 8, the sleeve being held in rigid contact with the shaft by a set-screw 18. The length of the weighted arm 16 may be adjusted on the sleeve by a set-screw. The inner end of the sleeve 17 has formed thereon a shoulder 19, and the outer end of the sleeve 7 of the bell-crank lever y has formed thereon a nose or shoulder 20, which engages with the shoulder 19 on the sleeve carrying the weighted arm 16, and thereby rocks or swings the arm 12, supporting the pouncing-belt, when the bell-crank is pulled back and forth by the link w, attached to the short arm x thereof and operated by the worm-wheel mechanism. The weighted arm draws the frame of the pouncing-belt toward the block G. The frame, supported by the rocking arm or standard 12, consists of a cylindrical shaft 14, having brackets 22 23 attached to each of its ends in any suitable manner, and to which are journaled pulleys 24 25, carrying the pouncing-belt 15.

The pulley 24, secured to the bracket 22 at the outer end of the frame, is provided with a groove 26, which receives the belt-pulley that gives motion to the pouncing-belt. The construction of this pulley 24, and the sleeve 100 on which it is journaled and secured to the bracket, is shown in cross-section in Fig. 8. The construction of the pulley 25, journaled at the opposite end of the frame, is shown in cross-section in Fig. 9.

A block 27, having two loose grooved pulleys 28 29, journaled opposite each other at its sides, is provided with an eye 30, through which the shaft 14 passes. The block is secured to the shaft by a set-screw 31. These pulleys 28 and 29 receive and return a belt-pulley 32, carried around the grooved pulley 10, mounted on the shaft 8, their use being to change the direction of the belt 32 from transversely of the belt-supporting frame to a direction parallel with the pouncing-belt. The belt 32 passes from the pulleys 28 29, mounted on the block 27, to and around pulley 24 and in the groove 26 therein and imparts motion to the pouncing-belt. The pulley 10, carrying the belt 32, is driven by a belt 33, carried from the grooved pulley 6, journaled to the shaft Z, supported in the sleeve on the end of the arm of the bracket Z'. The grooved pulley 6 is rigidly connected with grooved pulley 5, which is driven by the belt 3 4, previously herein described.

A collar 35, provided with a set-screw 36, is mounted on the shaft 14 and has formed eccentrically thereon an arm 37, the free end of which is beveled or rounded. This arm has secured to the outer side thereof a presser-foot or gage 38, curved at its lower end and carried around the end of the curved arm.

The straight part of the presser-foot or gage has a longitudinal slot therein to receive a set-screw 39, by which its length may be adjusted and its pressure against the article carried by the block G while undergoing the pouncing operation be limited, its use being for the purpose of holding the frame carrying the pouncing-belt at a proper distance from the block and of regulating the pressure of the pouncing-belt against the hat and preventing the belt from cutting too deep at any point during its movement between the tip and the base of the hat-crown. The presser-foot or gage 38 travels immediately back of the rear edge of the pouncing-belt. The movement of the pouncing-belt as it runs in contact with the hat may be from the tip upward and to the base of the crown on the upper circumference of the block or from the base of the crown down to the tip; but in the latter movement the gage will be in front of the pouncing-belt.

Motion is imparted to the operating mechanism which revolves the spindle by a band-pulley 40, driven by a line-shaft or counter-shaft pulley. (Not shown in the drawings.) The band-pulley 40 is carried by a driving-pulley 41, mounted on the outer end of a shaft 42, journaled in a bearing 43, formed on the upper end of a vertical standard rising to the height of the standard C, its base being secured to the floor, only the journal-bearing 43 at the top of the standard being shown in the drawings. The opposite end of the shaft 42 is journaled in the side of the collar D. The shaft 42 is shown in broken sections in Fig. 3. This shaft 42 is provided with a frictional gear-wheel 44, the circumference of which contacts with the face of the frictional disk F on the end of the spindle E. The frictional gear-wheel 44 is provided with a collar 45, which extends for a distance on each side thereof, but having a greater length projecting toward the driving-pulley. This collar has formed lengthwise of its interior circumference a spline or groove that receives a feather 46, attached to the circumference of the shaft 42 longitudinally thereof. A cylinder 47, having a cam-groove 48 formed in its exterior circumference that winds to its outer end and returns to its inner end, making one complete revolution thereon, is rigidly attached to the shaft carrying the worm-wheel M at the end opposite its bearing-support. An arm 49, having an antifriction-wheel 50 journaled at one of its ends and provided with two fingers 51 at its opposite end, that rest one on each side of the frictional gear-wheel 44 and loosely clasp the collar thereof, travels back and forth the length of the cylinder 47, with the antifriction-wheel 50 resting in the groove therein, the frictional gear-wheel 44 at the same time sliding back and forth on the revolving shaft 42 and with its periphery in frictional contact with the face of the disk F, thereby imparting a revolving motion to the spindle E,

to the worm-wheel M, and the grooved cylinder secured to the shaft of the worm-wheel. The speed at which the spindle revolves varies uniformly from fast to slow as the frictional gear-wheel 44 moves from near the spindle, at which point the speed is fastest, to the outer circumference of the disk, where it is slowest. 75

The pouncing or sandpapering belt 15 may be made of any suitable flexible fabric or material and the pounce or sand secured to the surface thereof by any of the various means used to cause such material to permanently adhere thereto. 80

A belt of felt or other material destitute of pounce or sand for burnishing the hat or article may be substituted for the pouncing or sandpapering belt when desired, the construction of the frame and the pulleys carrying the belt permitting of the ready removal of the belt therefrom and replacing it with another. 85

The weighted arm 16 when properly adjusted on the sleeve that supports it and 90 when the sleeve is also properly adjusted on its supporting-shaft swings the pouncing-belt frame toward the end of the spindle E, its movement in that direction being limited by the contact with each other of the nose or 95 shoulder formed on the sleeve that supports the weighted arm and the nose or shoulder on the sleeve formed on the end of the bell-crank lever y. This adjustment of parts may be so nicely made that the pouncing-belt will 100 press on the article carried by the block G with any degree of force required, its pressure being limited only by the presser-foot or gage 38, which travels in the rear. The pouncing-belt frame may be swung away from 105 the block by the hand of the operator, but little force being necessary when a nice adjustment has been made. 110

It will now be understood from the description of my hat-pouncing machine that the 115 means for rotating the spindle that carries the block on which the hat or other article to be pounced or sandpapered and the means for running the pouncing or sandpapering belt in contact therewith produce dissimilar 120 rates of speed. The spindle may be set in motion at the point where it will rotate at its lowest rate of speed and the pouncing-belt, moving at its highest rate of speed, swung into contact with the surface of a hat, the 125 speed of the spindle gradually increasing and the speed of the pouncing-belt decreasing or varying, or the spindle may be started at its highest rate of speed and the pouncing-belt brought into contact with the hat while the 130 belt is running at its lowest rate of speed. The speed of the two mechanisms may be so regulated that the cutting away of the surface of a hat at any point from the tip to the base of the crown, or vice versa, to too great 135 a depth is prevented.

In pouncing or sandpapering a hat from the tip to the base of the crown the spindle may be rotated at a high rate of speed at the

tip and the pouncing-belt at its lowest rate of speed, the relative speed of the spindle and of the belt being maintained when the crown of the hat is oval. When the pouncing-belt reaches the body of the crown, the speed of the pouncing-belt is increased to operate on the increased area, while the speed of the spindle is decreased to give time to the pouncing-belt to perform its work. Any or every part of the surface of the hat operated upon by the pouncing-belt may be gone over a second time or as often as desired. When the base of the crown is reached, the movement of the pouncing-belt may be back to the tip.

15 The trip or wiper U may be movably secured to the face of the worm-wheel at any operative point thereon to engage with the dog R' and drop the wheel out of contact with the spindle and at the same time rock the frame carrying the pouncing-belt away from the block.

Having thus described my invention, what I claim as new, and desire to secure by Letters Patent, is—

25 1. In a hat-pouncing machine, the combination with a spindle carrying a block for supporting a hat and means for rotating said spindle and varying its speed, of a pouncing-belt supported by pulleys journaled in a frame pivotally supported and provided with means connecting with means operated with said spindle for moving said belt in frictional contact with a hat supported on said block from the tip to the base of the crown, and means 30 for driving said belt, substantially as shown and described.

2. In a hat-pouncing machine provided with means for supporting and rotating a hat at a varying rate of speed, the combination with 40 said means, of a pouncing-belt supported on pulleys journaled in a frame, means for driving said belt and varying its speed, and means for carrying said belt in frictional contact with the surface of the hat between the tip 45 and the base of the crown thereof, substantially as shown and described.

3. A hat-pouncing machine, consisting of a spindle suitably mounted therein and carrying a block for supporting a hat, means for 50 rotating said spindle and varying the speed thereof, a pouncing-belt carried by pulleys supported in the opposite ends of a frame, means for driving said belt and means connecting with mechanism operating with said 55 spindle for swinging said frame and bringing said belt in frictional contact with the surface of a hat supported on said block, substantially as shown and described.

4. In a hat-pouncing machine having a rotating spindle carrying a block for supporting a hat and a swinging frame carrying a pouncing-belt run in frictional contact with the surface of the hat, the combination of a presser-foot or gage secured to said frame at 60 one of its ends and its free end adapted to rest in contact with a hat supported on said block and regulate the pressure of said poun-

cing-belt thereon, substantially as shown and described.

5. A hat-pouncing machine consisting of a 70 spindle suitably mounted and carrying a block for supporting a hat, means for rotating said spindle and varying the speed thereof, a pouncing-belt carried by pulleys mounted in the opposite ends of a frame pivotally supported, means for driving said belt and varying the speed thereof and means for swinging said frame and bringing said belt in frictional contact with the entire surface of the body of a hat supported by said block, substantially as shown and described.

6. A hat-pouncing machine consisting of a spindle suitably mounted and carrying a block for supporting a hat, means for rotating said spindle and varying the speed thereof, means connecting with said spindle for swinging a frame having a pouncing-belt carried on pulleys journaled therein, and bringing said belt in frictional contact with the surface of a hat when supported on said block, 85 and means for driving said belt in a direction opposite the direction in which said spindle is rotated and varying the speed of said belt, substantially as shown and described.

7. A hat-pouncing machine consisting of a 90 spindle suitably mounted and provided with a block for supporting a hat, means for rotating said spindle and varying the speed thereof, a worm-wheel rotated by said spindle, a pouncing-belt carried on pulleys journaled in 95 a frame pivotally supported, said pouncing-belt driven by a pulley-belt carried at a varying rate of speed, and means connecting with the shaft supporting said worm-wheel and with the frame in which said pouncing- 100 belt is mounted, for drawing said pouncing-belt in frictional contact with the surface of a hat supported on said block, between the tip thereof and the base of the crown, substantially as shown and described.

8. In a hat-pouncing machine provided with a spindle carrying a block for supporting a hat and provided with means for rotating said spindle and varying the speed thereof, the combination with said spindle, of a pouncing-belt carried by pulleys journaled at a distance from each other in a frame, said belt 110 driven by a belt-pulley run at a varying rate of speed, said frame pivotally supported and having means connecting with a worm-wheel 115 rotated by said spindle for moving said pouncing-belt in frictional contact with a hat supported on said block, between the tip thereof and the base of the crown, substantially as shown and described.

9. A hat-pouncing machine consisting of a spindle suitably mounted and carrying a block for supporting a hat, means connected with said spindle for rotating it and varying the speed thereof, a worm-wheel provided 130 with means for throwing it in and out of engagement with a worm on said spindle, a frame pivotally supported and carrying a pouncing-belt mounted on pulleys journaled

at a distance from each other in said frame, means for driving said belt and varying the speed thereof, and means connecting with said worm-wheel mechanism and with said frame for holding said pouncing-belt in operative contact with a hat supported by said block and carrying said belt from the tip of the crown of said hat to the base thereof, and from said base to said tip, substantially as shown and described.

10. A hat-pouncing machine consisting of a spindle carrying a block to support a hat, means for rotating said spindle and varying the speed thereof, a worm-wheel having means 15 to throw it in and out of engagement with a worm on said spindle, a link pivotally connected at one of its ends with the end of a lever rigidly attached to a shaft fixed in said worm-wheel, said link connected at its opposite end to one arm of a bell-crank pivotally supported by the frame of said machine, the other arm of said bell-crank provided with a sleeve supporting a shaft therein having a movable upright arm carrying a frame having 20 a pouncing-belt mounted on pulleys journaled therein, and means for driving said belt and varying the speed thereof, substantially as shown and described.

11. In a hat-pouncing machine provided 25 with a spindle having a block for supporting a hat secured to its end and connected with means for rotating said spindle and varying the speed of its rotation, the combination with said spindle, of a pouncing-belt carried 30 on pulleys journaled at a distance from each other in a frame supported by an arm pivotally secured on a shaft supported in a sleeve formed on the end of the arm of a bell-crank, said arm maintained in a laterally-movable, 35 upright position by a weighted arm rigidly attached to a sleeve secured to said shaft and provided with means locking with means on the sleeve on the end of said bell-crank to limit the movement of the arm supporting 40

said pouncing-belt in the direction of said block, a belt-pulley for driving said pouncing-belt, and varying the speed thereof, and a link connecting with said bell-crank and with a lever secured to a shaft fixed in a worm-wheel rotated by said spindle to draw 50 said pouncing-belt in frictional contact with the surface of a hat between the tip thereof and the base of its crown, substantially as shown and described.

12. In a hat-pouncing machine having a 55 spindle mounted therein and carrying a block for supporting a hat, said spindle having a worm thereon engaging with a worm-wheel rigidly mounted on a shaft carrying a crank secured thereto, means whereby said worm-wheel may be lifted into engagement with said worm and automatically throwing it out of contact therewith and means for rotating said spindle and varying the speed thereof, the combination therewith of a pouncing- 60 belt, said belt supported on pulleys journaled in a frame, said frame supported pivotally on a shaft secured in a sleeve formed on the long arm of a bell-crank pivotally supported in said machine, by an arm held in an upright position by an adjustable depending weighted arm secured to a sleeve rigidly attached to said shaft, a link attached to the short arm of said bell-crank and to the crank secured to the end of the shaft supporting 65 said worm-wheel, a belt-pulley run at a varying rate of speed supported on pulleys rigidly connecting with pulleys carrying a belt lengthwise of said pouncing-belt and around one of the pulleys supporting said belt, substantially as shown and described.

In witness whereof I have hereunto affixed my signature in the presence of two witnesses.

CHARLES H. REID.
